Atty's.

UNITED STATES PATENT OFFICE.

HUBERT WITTE, OF ST. LOUIS, MISSOURI, ASSIGNOR TO ST. LOUIS CAR COMPANY, OF ST. LOUIS, MISSOURI.

CAR-SEAT.

SPECIFICATION forming part of Letters Patent No. 748,903, dated January 5, 1904.

Application filed September 14, 1903, Serial No. 173,077. (No model.)

To all whom it may concern:

Be it known that I, HUBERT WITTE, a citizen of the United States, residing in the city of St. Louis and State of Missouri, have invented 5 certain new and useful Improvements in Car- Seats, of which the following is a full, clear, and exact description, reference being had to the accompanying drawings, forming part of this specification.

10 My invention relates to certain improvements in that class of car-seats known as "walk-over" seats, an illustration of which may be found in Letters Patent of the United States issued to the St. Louis Car Company 15 March 19, 1901, No. 670,190.

The invention consists in features of novelty hereinafter fully described, and pointed out in the claims.

Figure I is a front elevation of one end of 20 my car-seat with parts broken away. Fig. II is a vertical cross-section of the seat. Fig. III is a perspective view of the cushion-shifting mechanism. Fig. IV is a top or plan view of one end of the seat with the cushion 25 and back omitted.

As the two ends of my seat are duplicates, the description will be considered as applied to the entire seat, though but one end thereof is shown.

30 1 designates the pedestals of my seat, and 2 the end frames, which are provided with curved slots 3, to be hereinafter more particularly referred to. The pedestals 1 are united by longitudinal tie-bars 4, and the end frames 35 are secured to the ends of said tie-bars.

5 designates cross-bars mounted on the longitudinal tie-bars 4, of which more particular mention will hereinafter be made.

The above-mentioned parts form the frame 40 of the seat.

6 designates the back of the seat, which carries downwardly-extending arms 7. At each end of the seat is a link 8, the lower end of which has a slot-and-pin connection at 9

45 with the seat-arms 7. The upper ends of the links 8 are pivoted at 10 to the end frames 2, and the central parts of the links are widened and contain elongated openings 11.

12 designates a rock-shaft journaled in the 50 end frames 2 and extending longitudinally of the seat between said frames. This rock-

shaft has fixed to it near each end a foot-rest frame 13, having a pair of arms that carry foot-receiving rods 14, which move with said foot-rest-frame arms and with the rock-shaft 55 12 when said shaft is rotated.

15 designates levers, each fixed at one end to the rock-shaft 12 and pivoted at the other end at 16 to the back-arms 7. Seated in each lever 15 is a pin 17, that is adapted to ride in 60 the curved slot 3 in the adjacent seat end frame 2 and also in a slot 8' in the adjacent link 8.

Pivoted to the cross-bars 5 of the seat intermediate of their ends, as seen at 19, Figs. 65 II and III, are rockers 20, having downwardly-extending slotted arms 21 and upwardly-extending slotted arms 22. Each rocker-arm 21 is connected to the adjacent lever 15 by a pin 23, projecting from said lever to operate in the slot of the arm.

24 designates cushion-supports on which the cushion 25 is mounted. Seated in these supports are pins 26, that pass through the slots in the upper rocker-arms 22 to operate 75 therein.

When in the practical use of my seat the parts are to be shifted to reverse the position of the seat-back with respect to the cushion, the seat mechanism is operated as follows: 80 As the back 6 of the seat is shifted to the opposite side of the cushion from that at which it was previously located the levers 15 serve as pivot members on which the back is carried over. At the same time the lower ends of the 85 back-arms 7 operate pivotally in the lower ends of the links 8 and swing with said links to the opposite side of the seat. In the movement of the levers 15 during the shifting of the seat-back the rock-shaft 12, to 90 which said levers are fixed, is rotated, and therefore the foot-rest frames, with the foot-receiving rods, are oscillated forwardly, so that the rods will be carried into positions where they will constitute the least obstruction beneath the seat, as illustrated in Fig. II, so that there may be as near as possible a clear space beneath the seat. When the seat-back is shifted and the levers 15 moved, as stated, the pins 17, carried by said levers, 100 operate in the lower rocker-arms 21. Through this engagement the rockers 20 are oscillated

and their upper ends in engagement with the cushion-supports 24 through the pins 25 act to impart movement to the cushion-supports and cushion, thereby tilting said parts and shifting the cushion forwardly as the seat-back is swung thereover.

I claim as my invention—

In a car-seat, the combination of a frame having a curved slot, a cushion, supports for said cushion, a rock-shaft journaled in said frame, a foot-rest rigidly secured to said rock-shaft, a lever having its lower end rigidly secured to said rock-shaft and having a pin

intermediate of its ends for engagement in said curved slot, a reversible back pivoted to the upper end of said lever, a link pivoted to the frame and having slot-and-pin connection with the lower end of the reversible back, and a link having slot-and-pin connection with said lever and said cushion-supports for shifting the cushion when the back is reversed.

HUBERT WITTE.

In presence of—

A. DIEKMANN,
M. H. MURPHY.
